ATTORNEY

UNITED STATES PATENT OFFICE

HENRY M. NICHOLLS, OF CHICAGO, ILLINOIS, ASSIGNOR TO AMERICAN CAN COMPANY, OF NEW YORK, N. Y., A CORPORATION OF NEW JERSEY

SPOUT FOR CONTAINERS

Application filed April 23, 1928. Serial No. 272,003.

This invention relates in general to containers for holding and dispensing liquid contents, such as oil and the like, and has more particular reference to containers of this type embodying in their construction a pouring nozzle and pouring spout for discharging the contents.

The principal feature of my invention comprises a spout of the telescoping or disappearing type which is of simple, economical and novel construction and which is adapted to be permanently and securely attached to a container or to a nozzle part of a container, after the container has been completely filled and by merely pushing the spout in place. This permits the complete filling of the container without any interference by the presence of the spout.

Another important object of the invention is the provision of a telescoping spout adapted to have a liquid-tight fit with the container or with the nozzle part of the container, and which has simple, integral parts struck out from its body material which permit easy assembly without special tools and which keep the spout permanently secured to the container or nozzle part of the container.

Still another important object of the invention is the provision of a telescoping spout of a construction which eliminates the necessity of permanently attaching the spout to the container at the can making plant and which permits the attachment of the spout by the manufacturer, refiner or consumer of the contents without any special tools.

Numerous other objects and advantages of the invention will be apparent as it is better understood from the following description, which, taken in connection with the accompanying drawings, discloses a preferred embodiment thereof.

Referring to the drawings:

Figure 1 is an elevation of a liquid-holding and dispensing container embodying my invention. It shows the telescoping spout in inwardly extending or inoperative position and the nozzle of the container closed with the ordinary type of screw cap;

Fig. 2 is a vertical cross section through the upper part of the container, the nozzle

and the spout and shows the latter in position to be assembled, and

Fig. 3 is an enlarged view partially in section and partially in elevation of the fully assembled spout in extended or pouring position. 55

Although the invention will hereinafter be described as embodied in a container for holding and dispensing liquid contents, it will be readily manifest that the invention 60 may with equal facility be embodied in a container for holding and dispensing dry and granular products and other substances.

The preferred embodiment of my invention shown on the drawings comprises in general 65 a cylindrical sheet metal body 11 having a bottom end 12 and a top end 13 seamed or otherwise permanently secured thereto, a pouring extension or nozzle 14, a collar member 15, a gasket 16, a telescoping spout member 17 and a screw cap 18.

The top end 13 is double seamed to the container body at 19 and the metal of this top end, inwardly of the double seam 19, is bent downwardly to form a vertical wall 20, thence 75 inwardly at right angles to the wall 20 to form a horizontal sunken panel 21 having a circular pouring opening 22 located off center and in close proximity to a part of the annular double seam 19. It is customary to 80 locate the pouring opening of a container of this type near an edge or corner of the container to bring it as close as possible to the receptacle which is to receive the contents, to facilitate pouring and to more completely 85 empty the container.

The pouring extension or nozzle 14 is permanently attached to the panel 21 in a manner to be described and comprises a tubular member having screw threads 23 around its 90 central part. The lower end of this tubular member is arranged through the opening 22 and is crimped to the panel 21 about the opening 22. Flanges 24 and 25 are thus provided and embrace within their fold the sharp 95 edge of the panel defined by the pouring opening 22 and press upon opposite faces of the panel 21 about the opening 22. The metal of the flange 25 is returned upon itself, parallel with the flange 24, and thence extends up- 100

wardly and merges with the threaded central part of the tubular member. The nozzle 14, a short distance below its top edge, has an annular inward bead 26 which is engaged with a corresponding bead 27 of the collar member 15 and thereby locks the collar in place. Immediately above said annular bead 26, the metal of the nozzle 14 is formed into a straight vertical wall part 28 and the extreme edge of this wall 28 is turned inwardly to form an annular curl 29.

The metal of the collar 15, above its locking bead 27, runs parallel a short distance with the vertical wall 28 of the nozzle 14 and thence inwardly to form an annular horizontal ledge, locking flange or shoulder 30, and thence downwardly at substantially right angles to the ledge 30 to form a short depending wall 31, which is accurately sized and dimensioned to provide a tightly fitting annular surface for the sliding or telescoping spout 17, which is yet to be described in more detail.

The annular gasket 16, preferably of fibrous, liquid-proofed material, is tightly positioned between the curl 29 of the nozzle 14 and the collar member 15. It is rectangular in cross section. Its lower horizontal side rests upon and makes tight contact with the horizontal ledge 30 of the collar 15. Its outer vertical side makes tight contact with the inner surface of the straight wall 28 of the nozzle 14. Its inner vertical side is adapted to make liquid-tight engagement with the sliding or telescoping spout 17 and its upper horizontal side is engaged by the sharp biting edge of the curl 29 of the nozzle 14. This curl 29 is only formed after the gasket 16 has been positioned upon the horizontal ledge 30 and its function is to hold the gasket in place and to keep it in tight relationship with all the elements it contacts.

The spout 17 comprises a rectangular piece 45 of sheet metal bent into cylindrical shape and having its long side edges joined to form a side seam 32. The lower annular extremity of the cylindrical spout 17 is sharp and straight and the upper extremity is bent 50 outwardly to form a curl or hollow bead 33, which is adapted to serve as a stop to prevent the spout 17 from being slid or telescoped too far within the nozzle 14. The bead 33 also serves to hold in its hollow a wire which 55 is bent at two points 34 to form a loop 35 which serves as a handle or thumb piece to pull the spout 17 from the inwardly extending collapsed or inoperative position shown in Figure 1 to the outwardly extending or pouring position shown in Fig. 3. To provide space for the outward bends 34 of the wire, the metal of the spout and its top curl 33 are cut away at 36. A short distance 60 above the lower annular edge of the spout a

series of integral, resilient projections or lugs 37 are provided.

Each of these lugs 37 is formed by slitting the metal of the spout on three sides at right angles and bending outwardly the rectangular lug piece resulting from such slitting. These lugs 37 are all cut in the same horizontal plane and are spaced apart an equal distance from each other. Because of the metal used for the construction of the spout, these lugs 37 are resilient or spring-like in their action.

It will be thus readily seen that when it is desired to permanently assemble the spout 17 to the nozzle 14, the spout is placed in the position shown in Fig. 2 with the lower edge in registration with the vertical wall 31 of the collar 15. Pressure applied to the top of the spout will then move the spout inwardly of the collar 15. The lugs 37 will be pressed inwardly by their passage through the part 31 of the collar 15 and will spring outwardly again as soon as they have cleared the part 31. The spout 17 can then be moved within the nozzle 14 until the stop bead 33 meets the upper horizontal side of the gasket 16 and comes substantially on a level with the top of the curl 29 of the nozzle 14.

The loop or thumb piece 35 may then be turned inwardly from vertical to horizontal position so that it comes to lie within the opening of the spout 17, and a screw cap 18 of well-known construction may be screwed over the threads 23 and the nozzle 14 and spout 17 may be thus effectively closed. When the spout 17 is pulled outwardly to pouring position, as shown in Fig. 3, the expanded lugs catch behind the annular edge of the depending wall 31 and prevent any further outward movement of the spout.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container having an elevated nozzle formed with an inturned locking flange and with a pouring opening, and a pouring spout insertable within said opening to make liquid-tight engagement therewith, said spout having assembly means adapted to yieldingly pass and engage under said flange and effect permanent attachment of the spout to the container after the container has been fully constructed and filled.

2. A container having an elevated nozzle formed with an inturned locking flange and with a pouring opening, and a pouring spout insertable within said opening to make liquid-

tight engagement therewith, said spout having integral securing and yielding means adapted to yieldingly pass and engage under said flange and effect permanent attachment 5 of the spout to the container after the container has been fully constructed and filled.

3. A container having an elevated nozzle formed with an inturned locking flange and with a pouring opening, and a pouring spout 10 insertable within said opening and into liquid-tight engagement therewith, said spout having yielding securing means adapted to be compressed to clear said flange of the opening when the spout is to be assembled and to 15 expand after such clearance to serve as a permanent securing means.

4. A container having an elevated nozzle formed with an inturned locking flange and with a pouring opening and a pouring spout 20 insertable within said opening and into liquid-tight engagement therewith, said spout comprising a tubular member having yielding securing means adapted to be compressed by the passage through said opening to clear 25 the same when the spout is to be assembled and to expand upon such clearance to serve as a permanent securing means.

5. A container having a threaded pouring nozzle, a collar member having an inturned locking flange disposed within said nozzle, a liquid-tight packing between said nozzle and collar and a tubular pouring snout insertable within said nozzle and collar and adapted to make liquid-tight engagement 30 with said collar and said packing, said spout having securing resilient lugs adapted to be compressed to clear said collar when the spout is to be assembled and to expand under said locking flange after such clearance and to 35 serve as a permanent securing means, said spout being also adapted to be completely moved within said nozzle and said container and with the top edge of the spout substantially level with the top edge of the nozzle, 40 and a screw cap adapted to be screwed over said nozzle to close the nozzle and the spout.

6. A container having a pouring nozzle formed with an inturned locking flange around its pouring opening and a pouring 45 spout insertable within said nozzle and into liquid-tight engagement therewith, said spout comprising a tubular member having integral spring means adapted to be compressed to clear said opening when the spout is to be assembled and to expand under said flange after 55 such clearance to serve as a permanent securing means.

HENRY M. NICHOLLS.
